UNITED STATES PATENT OFFICE.

WILLIAM T. MAXWELL, OF PITTSBURGH, PENNSYLVANIA, ASSIGNOR OF THREE-EIGHTHS TO JOHN GASS, OF PITTSBURGH, PENNSYLVANIA.

SIGNAL SYSTEM.

Application filed March 21, 1925. Serial No. 17,278.

My invention relates to signaling systems, and is particularly directed to a system of warning signals for use on points where highways cross railway track at grade, or 5 where railroads cross one another.

One object of my invention is to provide a system wherein lamps are illuminated along the highway at distances from the crossing corresponding to the distance at 10 which a train which is approaching the crossing may be.

Another object of my invention is to provide an improved system of warning signals that are rendered operative when a 15 train is close to the crossing.

Another object of my invention is to provide a system wherein the position of the lamps that are illuminated will indicate from which direction a train is approach- 20 ing.

A further object of my invention is to provide an electrical signal system, the energy for which will be supplied from the locomotive or other railway vehicle.

Still another object of my invention is to simplify and improve generally the structure and arrangement, as well as the operation, of signal systems.

One form which my invention may take 30 is shown in the accompanying drawing wherein Fig. 1 is a side elevational view of a portion of a locomotive, showing diagrammatically one manner in which a portion of the apparatus may be connected thereto; Figs. 2 and 3 are end and side elevational 35 views, respectively, of a modified form of a contact shoe arrangement; Fig. 4 is an elevational view showing some of the warning signals and the manner in which they are positioned with respect to the crossing; Fig. 40 5 is a diagrammatic view showing the wiring arrangement of my system; Fig. 6 is a plan view showing the manner in which one of the contact bars of Fig. 5 may be made, and Fig. 7 is a sectional view thereof.

Referring to Fig. 1, I have shown a portion of a locomotive 2 upon which is mounted a generator 3 that may be driven from one of the locomotive driving axles 4, 50 through a belt 5. The generator 3 is connected through a conductor 6 with switches 7 and 8. The switch 7 is connected, through a solenoid coil 9, with a contact shoe 10 and to ground at 11, while the switch 8 is connected to ground through a solenoid coil 12.

The shoe 10 is normally held in position to effect contacting engagement with a conductor bar 13 by means of the electrode magnet 9. If the switch 7 be opened and the switch 8 closed, the magnet 12 will be energized 60 to move the shoe out of engagement with the bar 13. A spring 14 may also be employed for this purpose. When it is desired to bring the shoe into contact with the bar 13, the switch 8 is opened and the switch 7 is closed to energize the magnet 9, since the circuit is completed to ground at 11.

The shoe 10 may be secured to any portion of the locomotive, a locomotive tender or a car in position to automatically contact 70 with a bar or series of contacts 13, a plurality of which are provided along side the railroad track, as shown in Fig. 5 and explained more in detail hereinafter.

Instead of the shoe being in the form 75 shown in Fig. 1, it may take the form shown in Figs. 2 and 3, wherein the shoes 10^a are normally biased downwardly by a spring 15 and are connected through a vertically 80 slidable bar 10^b to a magnet 9^a that in turn may be connected with a generator and to ground as by conductors 6^a and 6^b.

A shoe 10 or 10^a will preferably be mounted at each side of the locomotive and may be connected to a single generator, in a 85 manner well known in the art.

The bars 13 are preferably each made in a plurality of sections as indicated in Fig. 6, in order to save material, and are each composed of a plurality of spaced contact 90 blocks 16, each of which may be mounted on a block or bracket 17, and which are connected by copper strips or similar conductors 18. The supporting members 17 may take the form of a continuous wooden bar if desired, or may be of any suitable material. The members 16, 17 and 18 just described enter into the construction of each of the bars shown in Fig. 5, such bars being indicated as 20, 26, 30, etc., each of which may 95 extend for some hundreds of yards.

While I have shown current as being supplied from the generator to the system, through a shoe and bars or series of contacts disposed along side the railroad rails, it will 105 be apparent that wires could be strung at a point above or along side of the railroad tracks and contact made from the generator through a trolley.

I have shown my device (Fig. 5) applied 110

to an ordinary double track railroad represented by the tracks A and B, that are crossed by a highway C.

- When the contact shoe or brush 10, which is carried by the locomotive, engages the contact bar 20, which may be located at say one mile from the crossing, the circuit is completed through conductors 21 and 22, lamps and conductor 24, to ground, at 25. 10 A driver on the highway, approaching the crossing, from either direction, will be apprised by the illumination of the lamps 23 that a train is approaching the crossing from the right, at a distance of about one 15 mile.

When the engine reaches the bar 26, which may be three-fourths of a mile from the crossing, the circuit will be closed through conductors 27 and 28, lamps 29, and conductor 24, to ground.

When the locomotive reaches the bar 30, which may be approximately one-half mile from the crossing, the circuit will be closed through conductors 31 and 32, lamps 33, and conductor 24, to ground, thus indicating to users of the highway that a train is approaching at a distance of about one-half mile.

A bar 34 is located at a distance of about 30 one-fourth mile from the crossing, and the brush 10 will thereby close a circuit through conductors 35 and 36, lamps 37, and conductor 24, to ground. A circuit will also be closed, through conductors 35 and 38, and solenoid 39, to ground. The solenoid 39 will close switch 40, thus completing a circuit through conductors 41 and 42, lamps 43 and conductor 44, to ground. Through a branch 45, a circuit is also completed through lamps 46 and conductor 47, to ground at 48. The lamps 43 and 46 burn steadily, as long as the shoe 10 is in contact with the bar 34. These lamps are preferably red and are disposed above the roadway, at the crossing, lamps 43 being between the track and a person approaching the track from one side of the railroad and lamps 46 are located at the opposite side of the tracks, so as to be readily seen by a person traveling in the opposite direction.

Current from the conductor 41 will flow through a conductor 49, solenoid 50 and switch 51 to ground, at 52. Current will also flow through conductor 42, switch 54, conductors 55 and 56, and lamps 57 and 58 to ground, until the coil 50 has become energized sufficiently to move the switches 51 and 54, that are connected by bar 53, against the tension of a spring 60, whereupon the circuit through conductor 55 will be broken and a circuit closed, through conductor 42, switch 54, conductor 61 and lamps 63 and 64, to ground.

Movement of the switches 51 and 54 from the position shown in Fig. 5 results in de-

energization of the coil 50, thus permitting the spring 60 to return such switches to the position shown. It will thus be seen that the switches will vibrate, to alternately make and break the circuits through the lamps 57-58 and 63-64, thus causing an intermittent illumination of such lamps, to more forcibly draw the attention of users of the highway to the fact that a train is quite close to the crossing.

The lamps 57 and 63 may be disposed above the roadway at one side of the railroad tracks and the lamps 58 and 64 at the other side thereof, so as to be more easily seen by persons approaching from either direction.

The bars 20, 26, 30 and 34 are substantially duplicated at the opposite side of the highway, as represented at 20^a, 26^a, 30^a and 34^a. These are connected to lamps 23^a, 29^a, 33^a, and 37^a, in the same manner as the first named bars are to the lamps 23, 24, 33 and 37.

Conductor 36^a, which is in the circuit of the bars 34^a and lamps 37^a, is connected, through a conductor 38^a to a solenoid coil 39^a, to ground. A switch 40^a connects conductor 38^a to conductors 41^a, 42 and 49. From 49, the lamps 43 and 46 are energized as described at length above.

The row of lamps 23, etc., at one side of the roadway will thus be illuminated when a train is approaching from that side, and the row of lamps 23^a, etc., will be illuminated by a train approaching from the other direction, while the lamps 43 and 46 will be illuminated by a train from either direction, as will also the intermittently energized lamps 57-58 and 63-64.

In order that a person standing near the track may determine at what distance the approaching train is from the crossing, I provide at one side of the roadway lamps 23^b, 29^b, 33^b, and 37^b connected to the conductors 22, 28, 32 and 36, respectively and through conductor 24^b to ground. At the other side of the roadway I provide lamps 23^d, 29^d, 33^d and 37^d connected through conductor 24^d to ground, and in parallel with lamps 23^a, 29^a, 33^a and 37^a. A person at the crossing can thus tell whether the train is a mile away, for instance, and whether he has time to cross the track, and whether the train is moving. For instance, the lamps 23^b or 23^d may be lit, and the succeeding lamps unlit. If this condition exists for a considerable period of time the observer will know that either the train is approaching very slowly indeed, or that it is at a stand-still.

If the engine is brought to a stand-still near a crossing, the engineer, in order to de-energize the danger signals and thereby permit traffic to move along the highway, may open switch 7 and close the switch 8, to raise the shoe 10 to circuit breaking position.

The conductor bars 20, 26, 30 and 34 of

track A are duplicated at the opposite side of the highway, as indicated at 20^b, 26^b, 30^b and 34^b. These last named conductors are connected to the lamps 23^a, 29^a, 33^a and 37^a, in the same manner as are the bars 20^a, 26^a, 30^a and 34^a so that such lamps will be illuminated by a train approaching the crossing on track A, past the bars 20^b, 26^b, etc.

Alongside the track B and opposite to the bars 20, 26, 30 and 34, I provide bars 20^c, 26^c, 30^c and 34^c; that are connected to the lamps 23, 29, 33, and 37 in the same manner as are the bars 20, 26, 30 and 34, so that the signals will be operated by a train on the track B as it approaches the crossing from that side of the roadway.

An additional signal, represented in Figs. 4 and 5 as a swinging "Stop" sign, may be caused to oscillate by means of electromagnets 67 and 68 that are connected to ground at one end and have their other poles connected, at 69 and 70, to conductors 61 and 55. The coils 67 and 68 will therefore be alternately energized to actuate the magnetizable arm of a pendulum 71, to cause it to oscillate about its pivot 72. One of these stops signs may be mounted at each side of the tracks above the roadway.

It will be apparent that various of the lamps and bars may be dispensed with in cases where it is desired to simplify the system. For instance, instead of a plurality of bars at each side of the track, a single bar could be located at a point some distance from the crossing and one or more lamps connected thereto, to be energized by an approaching train, and another contact bar disposed adjacent to the crossing to which another lamp or lamps, preferably red, might be connected to indicate that the train is dangerously close to the crossing.

Similarly the lamps 23, 29, 33, etc., can be disposed at any desired distance from the crossing, or be dispensed with entirely.

It is not necessary that current for the system be supplied from a locomotive, since batteries or other sources of electric current may be employed and automatically placed in circuit with the signals, by a moving train, in various well known ways.

I claim as my invention:

1. A signaling system adapted for use at railway crossings, comprising a plurality of electrical contact devices disposed at varying distances from the crossing, and a lamp

having connection with each of said contact devices and disposed in a direction transversely of the track at a distance corresponding to the distance at which its associated contact device is located from the crossing. 60

2. A signaling system adapted for use at railway crossings, comprising a plurality of electrical contact devices disposed at varying distances from the crossing, and a pair of lamps having connection with each of said contact devices and disposed in a direction transversely of the track at distances to either side of the track corresponding to the distance at which their associated contact devices are located. 65

3. A signaling system adapted for use at railway crossings, comprising a plurality of electrical contact devices disposed at varying distances from the crossing, a lamp having connection with each of said contact devices and disposed in a direction transversely of the track at a distance corresponding to the distance at which its associated contact device is located from the crossing, and a second lamp connected to each of said contact devices, each of said second lamps being located adjacent to the crossing. 70

4. Electrical signaling systems for railway crossings, comprising a plurality of contact devices disposed at various distances from the crossing in position to be engaged by a railway vehicle, means for completing circuits through said devices when so engaged, a lamp connected to each of said contact devices, a pair of electromagnets connected to one of said contact devices, switches for controlling the flow of current through said magnets, means in the circuit for intermittently actuating said switches to effect energization of said magnets alternately, and a swinging stop sign disposed adjacent to said magnets and operable thereby. 80

5. Electrical signaling systems for highway crossings at railways, comprising a plurality of contact devices disposed alongside the railway, at one side of the highway crossing, a signaling lamp connected to each of said contact devices and disposed along that side of the highway which is adjacent to said contact devices and placed at predetermined distances from the railway. 100

In testimony whereof I, the said WILLIAM T. MAXWELL, have hereunto set my hand.

WILLIAM T. MAXWELL.
